UNITED STATES PATENT OFFICE

97,823

DESIGN FOR A THERAPEUTIC HEATER

Ivan Ročić, New York, N. Y.

Application September 25, 1935, Serial No. 58,693

Term of patent 14 years

To all whom it may concern:

Be it known that I, Ivan Ročić, a citizen of the Kingdom of Croatia, Jugoslavia, and a resident of the city of New York, county of New York, and State of New York, have invented a new, original, and ornamental Design for a Therapeutic Heater, of which the following is a specification, reference being had to the accompanying drawing, forming part thereof.

Figure 1 is a top or plan view, Figure 2 is a

front view, Figure 3 is a side view and Figure 4 is a sectional view on line $a-a$ of Fig. 1 respectively of a therapeutic heater showing my new design.

I claim:

The ornamental design for a therapeutic heater as shown.

IVAN ROČIĆ.
